METALLURGICAL FURNACE

William J. Thomas, Great Falls, Mont., assignor
to Anaconda Copper Mining Company, New
York, N. Y., a corporation of Montana

Application January 20, 1934, Serial No. 707,452

1 Claim. (Cl. 110—99)

This invention relates to reverberatory furnaces, and has for an object the provision of an improved method of construction for reverberatory furnaces. More particularly, the invention 5 contemplates the provision of improved arched reverberatory furnace roofs and an improved method of constructing such roofs.

The roof of a reverberatory furnace, more than any other part thereof, is exposed to the full 10 heat of both the flame and the gaseous products of combustion, which sweep through the furnace close to the roof. Accordingly, the material from which the roof is constructed must be chosen from amongst those substances capable of withstanding very high temperatures. Other 15 considerations, however, also influence the choice of the material to be used. For instance, a reverberatory furnace roof must be made from a good heat-insulating material, for otherwise great 20 quantities of heat would be lost therethrough. The material of the roof must be capable of withstanding the attack of corrosive substances which are carried in contact therewith by the gases 25 passing through the furnace. The roof must be mechanically strong, and to be commercially 30 successful the material from which it is constructed must be relatively inexpensive.

Hitherto the material most generally used for the construction of reverberatory furnace roofs 35 has been silica, because more than other known material silica combines good heat-insulating properties, fair resistance to corrosion, and fair mechanical strength with relative cheapness.

It has long been known, however, that certain 40 more costly materials, while not generally possessing better heat-insulating properties, have considerably greater resistance to corrosion and greater mechanical strength than has silica. Magnesite, chrome, carborundum, and zirconia 45 are a few of the materials which might be listed in this category.

A few experimenters, recognizing the chemical 50 and mechanical advantages of such materials as magnesite, chrome, carborundum, and zirconia over silica, have constructed reverberatory furnaces using one of these materials for the roof, but invariably, except where the furnace was extremely small, the increased cost of the special roof material has more than offset the chemical and mechanical advantages attained by its use.

I have found by long experimentation that 55 good results can be obtained by applying a lining of suitable refractory to the underside of a reverberatory furnace roof, the main body of the roof being made of some comparatively inex-

pensive material. In this manner, a roof having such chemical and mechanical properties as are well adapted to resist the destructive actions of high temperature and contact with corrosive substances may be constructed at a comparatively 5 low cost.

The development of a roof of this nature has been attended by many difficulties. The lining can not be made self-supporting in industrial practice, and it must, therefore, be attached to 10 the main body of the roof in such a manner as to be supported thereby. The means whereby the lining is attached to the main body of the roof should be sufficiently flexible to allow for 15 differences in the thermal expansion of the lining material and the material of the outer portion of the roof, yet it must be sufficiently firm to support the lining in its proper position. This result I have accomplished in a number of ways.

The simplest and probably the least expensive 20 method for this purpose comprises constructing both the lining and the roof proper of ordinary straight-sided or rectangular bricks, such as are obtainable upon the market in commercial quantities. The bricks used in the lining are composed of the desired special refractory, and are laid in the form of an arch spanning the width of the furnace. Periodically, I lay bricks of the 25 lining in such a manner that their longest dimension extends substantially vertically, while 30 the balance of the bricks of the lining I lay with their longest dimension extending substantially horizontally. The bricks comprising the main body of the roof are then laid upon the upper side of the bricks of the lining in such a manner 35 that the spaces between the upwardly extending bricks of the lining are filled with the bricks of the main body of the roof, and the main body of the roof is continued upwardly, in the usual manner, above the bricks comprising the lining, 40 until an arched roof of desired thickness and mechanical strength is obtained.

A procedure such as outlined above is entirely 45 satisfactory for furnaces of small size, or in those cases where only a portion of the arched roof is to be lined with special refractory. In large furnaces, and in those where temperature variations are frequent and/or of considerable magnitude, I prefer to use a series of bricks of such design 50 that the lining and the main body of the roof are more completely interlocked. This may be accomplished by manufacturing the bricks of the main body of the roof in such a form that they are provided at one end (the end adjacent the 55 lining) with protuberances which interlock with

corresponding recesses in the bricks of the lining. By the use of such specially constructed interlocking bricks, I am enabled to attain a positive engagement of the lining with the main body 5 of the roof, whereby the lining remains firmly yet flexibly attached to the roof through even the most rigid and extreme variation in temperature likely to be encountered in a reverberatory furnace.

10 For the purpose of more adequately illustrating my invention, I will refer to my preferred practices, as illustrated in the accompanying drawings, in which

Fig. 1 is a longitudinal sectional elevation of a 15 reverberatory furnace of conventional design equipped with a roof embodying the invention;

Fig. 2 is a sectional elevation of the furnace taken substantially along the line 2—2 of Fig. 1;

Fig. 3 is a fragmentary plan cross-section of 20 the roof taken substantially along the line 3—3 of Fig. 2;

Fig. 4 is a fragmentary longitudinal sectional elevation of a reverberatory furnace of conventional design equipped with a modification of 25 the roof illustrated in Figs. 1 to 3;

Fig. 5 is a fragmentary plan cross-section of the roof taken substantially along the line 5—5 of Fig. 4;

Fig. 6 is a fragmentary longitudinal cross- 30 section of a reverberatory furnace roof constructed from interlocking bricks of a preferred design;

Fig. 7 is a plan view of the underside of the 35 roof section shown in Fig. 6; and

Fig. 8 is a transverse sectional elevation of a reverberatory furnace roof embodying a modification of my invention.

Figs. 1 and 2 show conventional cross-sections 40 of a reverberatory furnace 10 having a floor 11 and a roof 12. The furnace is provided with side walls 13 and an end wall 14 having openings 15 and 16 therein through which fuel and air may be admitted to a grate 17 on which combustion of the fuel takes place. The products of combustion 45 pass upwardly from the grate and over a bridge wall 18, sweep the length of the furnace between the under surface of the roof 12 and the upper surface or metal line 20 of the molten mass within the furnace, and pass out of the furnace 50 through a flue 21.

In this furnace the roof 12 is constructed according to the method of my invention. The main body 22 of the roof 12 is constructed of some comparatively inexpensive refractory, for 55 example silica, and the lining 23 is constructed of a special refractory, for example magnesite, having desirable properties such as, for example, resistance to corrosion. The lining is bonded to the main body of the roof in a manner to be 60 described.

For the purpose of simplicity in rendering the following disclosures, I shall assume that in the furnace the main body of the roof is constructed of silica bricks, and that the lining is constructed 65 of magnesite bricks, but it will be understood that other types and combinations of materials may be employed in their stead.

Alternate magnesite bricks 24 are laid with one end lowermost and adjacent the interior of 70 the furnace, and with the other end extending upwardly. Intervening magnesite bricks 25 are laid on their side, preferably, as shown in the drawings, with their surfaces of greatest area 75 lying in substantially vertical planes. In this

manner spaces 26 are provided between the upwardly extending bricks 24.

On top of the magnesite bricks the silica bricks are laid in such a manner as to fill the spaces 26 and to build the main body of the roof 22 to 5 the depth necessary to insure a proper degree of mechanical strength. The upwardly extending bricks 24 serve to bond the lining to the main body of the roof in a manner very similar to that whereby dowel pins may be used to join two 10 boards together.

Fig. 3 shows a fragmentary sectional plan view taken substantially along the line 3—3 of Fig. 2. There the alternate magnesite bricks 24 are shown having the spaces therebetween filled with 15 the silica bricks comprising the main body of the roof 22.

A modification of the above-described method of bonding the lining to the main body of the roof is shown in Figs. 4 and 5. Fig. 4 shows a 20 fragmentary portion of a reverberatory furnace 10 with a flue 21 for the escape of the gaseous products of combustion. The roof 12 of the furnace has bonded to its underside a lining 23.

In this modification two intervening magnesite 25 bricks 25, laid on their sides, are used between each alternate upwardly extending magnesite brick 24. A sectional plan view of this modification is shown in Fig. 5, taken substantially along the line 5—5 of Fig. 4, wherein the alternate 30 bricks 24 are shown having the spaces therebetween filled with silica bricks comprising the main body of the roof 22.

A lining constructed as shown in Figs. 4 and 5 35 has the advantage of requiring a smaller quantity of special refractory than does the lining construction described in connection with Fig. 1, but it probably does not possess as firm a bond 40 between the lining and the main body of the roof.

The roof 12 is built in the conventional arched form, and is supported in the usual way upon the side walls. As is customary in the art, the arch is restrained from flattening out by skew-backs 27 which may be held in place by buckstays 45 and tie-rods (not shown). I have found that a reverberatory furnace roof constructed in this fashion and having a lining bonded to the underside thereof in the above-described manner is 50 very strong, and excellently withstands the corrosive action of hot furnace gases and other substances brought in contact therewith by the hot furnace gases.

In one test, only a portion of the roof of a copper refining furnace was protected by a lining 55 of magnesite bonded in the above described manner to the silica comprising the main body of the roof. The balance of the under-surface of the roof was silica. An expansion joint was provided between the portion of the roof which was 60 lined with magnesite and the balance of the roof, partly to prevent fluxing of the silica under-surface with the magnesite under-surface. After a forty-charge run the furnace was shut down and, after cooling, the roof was inspected.

It was found that of a total magnesite surface area of 6,864 square inches, a spot of about 324 square inches, or 4.72% of the total magnesite area, had spalled to a depth of about three-quarters to one inch. At this spot, however, magnesite still remained to a depth of about 3½ inches, or over 75% of the original 4½ inches laid down. The balance of the magnesite lining was apparently unaffected by spalling. The only other defect noted comprised 75

a longitudinal slippage of a small portion of the lining. This portion had slipped downwardly to about an inch below the level it had originally occupied. I attribute these slippage conditions to the unequal thermal contraction of the magnesite and silica while the furnace was cooling to room temperature. Although close inspection of the roof was impossible during the operation of the furnace, the magnesite lining was visible through the charge doors, and throughout that period these conditions did not become apparent. Compared to the silica under-surface adjoining it, however, the magnesite was in excellent condition. While the silica showed very substantial signs of corrosion, and had deteriorated to a marked degree, the magnesite, with the exceptions above noted, was intact.

To produce an even firmer bond between the lining and the main body of the roof than is possible by the above methods of construction, I use a series of bricks of special design, as illustrated in Figs. 6 and 7. In this modification, the main body of the roof is constructed of alternately short and long silica bricks. The alternate long bricks 30 extend below the intervening short bricks 31. The alternate long bricks 30 are enlarged at their lower ends by protuberances 32, which fit into corresponding recesses 33 in the alternate magnesite bricks 34 of the lining. The upper ends of the alternate bricks 34 of the lining are disposed adjacent the lower ends of the intervening bricks 31 of the main body of the roof, while their lower ends are adjacent the interior of the furnace. Intervening magnesite bricks 35 are provided to interlock with and to fill the spaces between alternate bricks 34 of the lining.

In this manner the alternate bricks 34 of the lining are held in place by the alternate bricks 30 of the main body of the roof. The intervening bricks 35 of the lining are in turn held in place by the alternate bricks 34 of the lining. This method of construction firmly bonds the lining to the main body of the roof by causing the former to actually interlock with the latter. Accordingly, slippage of the lining downwardly is impossible unless the bricks are broken.

Although I have shown specifically a series of interlocking bricks, the protuberances and recesses of which are provided by making the cross-sections thereof substantially trapezoidal in shape, or of such a shape as to be readily resolvable into two trapezoids (such as in the case of the alternate bricks 34 of the lining), it will be understood that I do not limit myself to bricks having precisely this shape. Although I have herein described my preferred shape of interlocking bricks, other shapes having interlocking protuberances and recesses may be utilized.

I have found that within a reverberatory furnace, a focal point of corrosion appears to be at the line where the roof joins the side walls. Accordingly, it is sometimes possible to effect substantial diminution in the amount of corrosion that occurs, if corrosion-resisting refractory is placed along this line. Fig. 8 shows a transverse

cross-section of an arched reverberatory furnace roof 12 having corrosion-resisting refractory 40 disposed on the underside of the roof and directly over the side walls 13. This corrosion-resisting refractory (for example, magnesite) may be continued inwardly toward the center of the arched roof 12 for any desired distance. Fig. 8 shows one extreme, with the corrosion-resisting refractory 40 extending inwardly only to the inner surface of the side wall 13. Fig. 2 shows the other extreme, where the magnesite has been carried inwardly from a point directly over each side wall to the center of the arch, thus completely lining the arch. It will be understood, however, that I do not limit myself to a type of construction wherein the lining is carried inwardly to a point directly over the side walls.

In constructing reverberatory furnace roofs in accordance with my invention, it is advisable to provide the customary cross-section expansion joints. According to some present practices cross-section expansion joints are provided at intervals of approximately ten feet to take care of longitudinal expansion, the widths of opening of the joints being determined by the amount of expansion of the roof materials at the maximum furnace temperature. Lateral expansion is taken care of automatically by the rise and fall of the roof under the influence of heat at various temperatures, or mechanically by adjustment of the tie-rods which support the buckstays.

By constructing a reverberatory furnace roof in accordance with my present invention, it is possible to attain the following advantages:

(a) The full strength and heat insulating properties of a heavy roof may be obtained without incurring the expense entailed by using the bricks of the lining for the full thickness of the roof.

(b) A refractory surface capable of withstanding the corrosive action of hot furnace gases and fume is provided.

(c) The roof may be renewed in sections without loss of the remaining roof.

(d) Should the furnace lining be burned through to the main body of the roof, there still remains sufficient strength and thickness of the roof to permit completion of a reasonable furnace campaign before shutting down for repairs.

I claim:—

A reverberatory smelting furnace comprising side walls terminating in substantially horizontal upper bearing surfaces for at least a portion of their length, an arched roof bearing upon said upper horizontal surfaces, skewbacks on said upper horizontal surfaces for restraining flattening-out of the arched roof, and a lining of corrosive-resistant refractory material for the underside of said roof, said lining extending between the juncture of the inner side of the side walls and the roof and the skewbacks and being interposed between said horizontal surfaces of the side walls and at least a portion of the roof resting thereon.

WILLIAM J. THOMAS. 65
